UNITED STATES PATENT OFFICE.

PAUL G. HANSON, OF ROCHESTER, MINNESOTA.

SAFETY RAILWAY-SWITCH.

SPECIFICATION forming part of Letters Patent No. 254,870, dated March 14, 1882.

Application filed September 7, 1881. (No model.)

To all whom it may concern:

Be it known that I, PAUL G. HANSON, of Rochester, in the county of Olmsted and State of Minnesota, have invented a certain new and useful Improvement in Safety Railway-Switches, of which the following is a specification.

This invention relates to switches for railway-tracks, and more particularly to the class known as "split switches," and it is my object to arrange these switches in such a manner that the adjustment and changing of the switch are under control of the engineer in charge of the approaching locomotive, and that under no circumstances can the locomotive run off the track in consequence of a displacement of the switch.

Therefore my invention consists of the peculiar arrangement of the switch-rails and their connections, and in combination therewith of certain attachments to the pilot of a locomotive for adjusting and controlling the switch, all as more fully hereinafter explained and specifically claimed.

In the drawings forming part hereof, Figure 1 represents a plan view of the switch and of the pilot of an approaching locomotive; Fig. 2, a sectional elevation of a side lever, to be presently described; Fig. 3, a cross-section on line $\alpha\alpha$ in Fig. 1; Fig. 4, a longitudinal section, and Fig. 5 a plan view, of one of the guide-shoes for the shifting-bar, and Fig. 6 is a side elevation of another guide-shoe.

Like letters designate corresponding parts in all the figures.

A A' denote the rails of the side track of a railway, and B B' the rails of the main track, each of which tracks is provided with a split or pointed rail, A' and B', that is supported on a sole-plate, α and α' . These sole-plates, as well as the rails, are rigidly secured upon sleepers C C in the usual manner. The split or pointed rail end B' is rigidly secured upon its sole-plate α' , to be stationary thereon, at a sufficient distance from the rail A to leave an open channel for the flanges of the passing wheels to pass between when the locomotive is to follow the main track, and when it is to follow the side track the wheel-flanges will ride upon the sole-plate α' until they pass the gap and the point of the rail end.

The split or jointed end of rail A' is ar-

ranged to slide laterally upon the sole-plate α , between rail B and the guard-rail D, a distance that is just sufficient for forming a channel for the wheel-flanges either to pass between the rail B and rail end A' or between the guard-rail D and the rail end A', according to the track that is to be followed.

The rail A' is held steady against the lateral stress of the wheels by one or several bars, E, that form a gripe or dovetail over the bottom flange of the rail at one end, and are guided in a hole of sole-plate α' on their opposite end.

The end of a bar, F, is connected to the rail A' near its pointed end. This bar F is passed through a slot in the sole-plate α' , and its exterior end is pivotally connected to the side lever, G, which is pivoted in the fulcrum-plate g , that is secured upon one of the sleepers C. This lever G is bifurcated at its ends where it carries wheels h h' . A cross-bar, H, is placed underneath the rails, with its upset ends sliding upon rollers i in guide-shoes I, so as to be permitted a longitudinal sliding movement therein.

Underneath the wheel h' the forked end of the lever G is pivotally connected to the cross-bar H by the end of the bolt that carries the wheel h' being passed through a hole in said cross-bar. Another lever, K, is pivoted at one end upon one of the sleepers C, and its opposite bifurcated end carries a roller, j, and is connected to the cross-bar H in a similar manner as lever G. The rollers h' and j , being at opposite sides of the track, are placed a sufficient distance apart for the pilot of the locomotive to pass between, and for certain side attachments to the pilot to be brought in contact with either one of said wheels for pushing the bar H laterally in either direction, whereby the end of rail A' will be shifted either against the rail B or against the guard-rail D, as it may be intended to either follow the main or side track.

The guide-shoes I and I', forming guides for the cross-bar H, and having each a roller, i , that is pivoted in a socket underneath the cross-bar for supporting the same and for reducing its friction, have a cap-plate, l, which will hold the cross-bar in the guides and will protect the roller i against rain and dirt. One of the guide-shoes is larger than the other, and has a tapering slot, m, and the cross-bar at this point

also has a short slot, *n*, for a crow-bar, *M*, to be inserted, by which the switch may be operated by hand, if desirable, or as may become necessary in case a locomotive is to pass that 5 has not been provided with the necessary attachments to its pilot for making the changing of the switch automatic.

O O are the foremost wheels of a locomotive, and P is the pilot or cow-catcher. Against the 10 sides of the two diagonal bottom rails of this pilot I hinge two flat bars, Q Q', by staples *p*, and the rear ends of these bars Q Q', by short links *q*, I connect with the ends of a cross-bar, R, that is guided in brackets *r* to reciprocate 15 therein. This bar R is sufficiently longer than the width of the rear bottom end of the pilot that when one bar, Q, is brought to lie close against the diagonal rail of the pilot, the bar Q' will stand at an angle off the other pilot- 20 rail, and vice versa. The thus projecting bar Q or Q' is to adjust and move the switch by coming in contact with either wheel *h* or *j*, and by pushing the cross-bar H in either direction the lever G, with bar F, is compelled to shift 25 the end of rail A for leading the train upon either track; and for the purpose of bringing the operation under the control of the engineer, I connect the bar R by a pitman, S, with a crank, T, which latter, with a one-half revolution 30, will retract the projecting bar Q and will project the retracted bar Q', or vice versa, and which with one-quarter turn will stand at the intermediate position, and will hold the bars Q and Q' extended at equal distances and out of 35 action. This crank T may be operated by a hand-crank, U, or a lever from the inside of the cab of the locomotive, and for that purpose the connection between cranks U and T may be made in any suitable manner by shafts, 40 swivel-joints, or gearing, or by sprocket-wheels and chains, or a combination of either devices, that depending upon the general style and construction of the locomotive to which the attachment is to be made.

45 In Fig. 1 of the drawings the switch is shown in the position when the locomotive would have to follow the side track, while the side bars, Q and Q', to the pilot P are adjusted to change the position of the switch for the locomotives to follow the main track, which change will be made sufficiently in advance of the foremost locomotive-wheels to insure the reliability of the device.

The roller *h* on the opposite end of side lever, G, is intended only for a train coming 55 from the opposite direction from that shown in Fig. 1 in the drawings, and over the side track. In this case the said roller *h* is only to clear the pilot of the locomotive with the bar 60 Q retracted, when the end of rail A' lies close against the rail B, while if otherwise the roller *h* will come in contact with the pilot and will be pushed in an outward direction, whereby said rail A' will be shifted to occupy the desired position before the wheels of the locomotive throw any weight upon it. In case 65 a train is coming from the opposite direction

over the main track and the rail A' would be in position, as shown in Fig. 1 of the drawings, the flanges of the wheels would shift 70 said rail A' toward and against the guard-rail D, there being no weight upon it then that would hinder its easy pushing out of the way.

As will be noticed with the above-described arrangements, the engineer does not depend 75 on the faithful performance of the switchman; but he has the switches entirely under his control, thereby obviating accidents so frequently brought about by the careless adjustment of the switches.

The device, as will be noticed, is very simple, can be made very durable in its construction, and cannot well get out of order.

Instead of employing a crank, T, and pitman S for reciprocating the bar R, said bar R 80 may be provided with rack-teeth, and may be operated by a pinion or any other well-known device for bringing about a reciprocating movement may be applied as well.

For the purpose of extending the guide for 90 the wheel-flanges when following the main track, I bolt an iron block, *u*, against the side of the split rail A', which has chamfered ends for the wheel-flange to bear against and push the rail A' aside.

Under the lever G, at the end toward wheel *h*, I place a shoe, T, that has a rib with inclined sides projecting on its top face, over which the lever will have to slide when changing position, and which rib, by the weight and 100 spring-power of said lever G, will hold said lever to a certain extent in either of its two positions.

What I claim as my invention is—

1. In combination with rails A A' and B B', 105 sole-plates *a a'*, and guard-rail D, the bar H, guide-shoes I I', side lever, G, and connecting-bar F, all constructed and arranged for automatically adjusting the switch-rail A' from the pilot of an approaching locomotive, substantially in the manner set forth.

2. In combination with rails A, A', B, and B', sole-plates *a a'*, and guard-rail D, the cross-bar H, guide-shoes I I', levers G and K, with wheels *h*, *h'*, and *j*, and connecting-rod F, all 115 constructed and arranged for automatically adjusting the switch-rail A' from the pilot of an approaching locomotive, substantially in the manner set forth.

3. In combination with the switch-rail A, connected by bar F with lever G, which is again connected by bar H with lever K, the pilot of a locomotive, having side bars, Q Q', connected by a bar, R, and arranged to be adjusted from the cab of a locomotive by any 125 suitable devices and connections, all substantially in the manner and for the purpose specified.

4. In combination with the switch-rail A', connected by bar F with lever G, which again 130 is connected by bar H with lever K, such levers G and K having wheels *h*, *h'*, and *j*, the pilot of a locomotive, having side bars, Q Q', connected by bar R, and arranged to be ad-

justed by a crank, T, and pitman S, all substantially in the manner and for the purpose described and shown.

5. The combination, with the automatic switch, as described, of the shoes I and I', forming the guides for cross-bar H, and having rollers i and cap-plates l, all substantially as and for the purpose set forth.

6. In combination with the automatic switch

described, the cross-bar H, having slot n, and the guide-shoe I', having tapering slot m, all substantially as and for the purpose described and shown.

PAUL G. HANSON.
